ELASTIC LACE BRAID

Application filed June 18, 1932. Serial No. 616,813.

This invention relates to lace braid and particularly to elastic lace braid where the elastic strands are braided with non-elastic strands to prevent "creeping" of the elastic strands and to permit the elastic strands to be stretched to their elastic limit.

The particular braided elastic fabric with which this invention is concerned is manufactured on what is known as a one thread lace machine. That machine is similar to the ordinary braider, but differs from it in that it has individually controlled carriers governed by a jacquard mechanism so built that each carrier is controlled in its passage in the machine race track or circle by a predetermined pattern.

Braided with the elastic threads are two distinct sets of non-elastic threads, the transverse or braiding threads and the longitudinally running binding threads.

The introduction of elastic strands into the braid in a stretched condition from a moving carrier traveling in a race track is the only way in which the running binding thread paralleling the longitudinal elastic strands will receive sufficient yardage to allow the rubber or elastic, after braiding, a stretch approaching its elastic limit.

A lace braided fabric made in that way, when released, has its parallel running binding threads laying loosely next to the longitudinal rubber strands. As soon as tension is placed on the fabric, these binding threads are forced tightly against the taut rubber strands of the fabric, subjecting them to a somewhat similar tension to that given the rubber.

Moreover, it is well-known that rubber itself does not shrink, but the various other textile fabrics contained in any braid have a known shrinkage under varied conditions such as heat, perspiration, moisture absorption, etc. Thus, there is frequently a certain amount of shrinkage which the construction outlined above does not make allowance for.

The object of the present invention is to provide an improved elastic lace braid.

A further object of the invention is to provide an elastic lace braid where the non-elastic longitudinal binding threads will

never be placed under tension even when the rubber strands are stretched to their elastic limits.

Still another object of the invention is to provide an elastic lace braid with the above attribute and which is so constructed that there will be no "creeping" of the elastic strands.

According to the invention, my improved elastic lace braid is manufactured by feeding taut but untensioned elastic warp strands from stationary supply sources, feeding non-elastic threads from bobbins in the race track or circle so as to braid or interconnect in lace effect the several elastic warps, and feeding other non-elastic threads from bobbins in limited portions of said race track longitudinally and from side to side of a single warp, and in which the last bobbins change from one side of the elastic warp to the other at the point where the non-elastic braid threads cross the elastic strands and which, at that point, bind the said braiding threads to said elastic strands.

Between the points where the first non-elastic threads cross the elastic threads the longitudinal non-elastic threads will be twirled or looped, thus providing expandible portions which will not be placed under tension even when the elastic strands are stretched to their elastic limit.

The drawing illustrates an embodiment of the invention and the views therein are as follows:

Figure 1 is a developed portion of the race track or race circle, and is for the purpose of description only, and

Figure 2 is an exploded view of a portion of the finished fabric or braid, clearly illustrating the braiding and binding non-elastic threads in relation to the elastic strands.

Referring now to the drawing, and particularly to Figure 1, the longitudinal elastic strands are fed from spools 3 located at some convenient point beneath the race plate 4. The elastic strand is fed from the spool up through a tube 6 which extends through a hole in the center of the gear stud 7 so that the elastic warps are fed upward into the middle of the race track 8 in such a way that a

specially constructed jacquard formation interlocks in a set position.

The carriers $a^1, a^2; b^1, b^2; c^1, c^2$; and d^1, d^2 ; are controlled by jacquard movement so that they revolve around the circles on each side 5 of the elastic warps and also cross to the other side of the gear studs 7 through which the warps A, B, C and D are fed.

With each motion of the one thread lace machine and its jacquard attachment, the carriers $a^1, a^2; b^1$, etc., form a twirling of the threads along the longitudinal elastic strands A, B, C and D in the manner shown in Figure 2 so that the loops or pockets P are produced.

At the same time the carriers $m^1, m^2; m^3, m^4; m^5, m^6; m^7$ and m^8 ; are operating in a manner determined by the jacquard movements so that either mesh background or whatever weave is desired, can be produced.

In Figure 2 a background of mesh is shown 20 and it is to be understood that this may be varied, as desired, by the changing of the jacquard movements through the patterns cards.

In order that the longitudinal rubber strands may be kept from "creeping", an interlocking of the running parallel threads is made with the longitudinal rubber strands at certain intervals determined by both design and jacquard machine, and in the present 25 instant, as indicated at 9.

The spools 3 are mounted in anti-friction bearings and may be of such size as will permit the elastic strands to be withdrawn from the same without stretch, the size of the 30 spools being limited only by such weight as will not necessitate stretching of the elastic strands to turn the spools. If desired, suitable feed-off mechanism can be arranged for feeding out the elastic strands as required by the machine, and just sufficient to keep the 35 same taut, but unstretched.

The spindles $a^1, a^2; b^1, b^2; c^1, c^2$; and d^1, d^2 ; are provided with the usual tensioning means which may be varied and which determines the amount of feed from the bobbins on the carriers so that the loops and pockets P of the twirled longitudinal non-elastic strands may be varied to suit every individual case, the object, however, being that the loops and pockets of this twirled thread 45 shall be sufficient to permit the elastic strand along which it lays to be stretched to its elastic limit without placing any tension whatsoever upon the non-elastic threads.

With this method of construction a maximum stretch of as high as 100% to 125% 50 can be imparted to the complete fabric without any resulting strain on the longitudinal threads which bind and interlock the longitudinal elastic strands under even pressure 55 from all sides. Thus the elimination of strain on the binding or interlocking structure of the braid adds greatly to the wear of the fabric, as even with a maximum stretch 60 of the elastic strands, the longitudinally

running threads are permitted to remain relaxed. By means of the introduction of elastic strands into a lace braided fabric, with the elastic under normal tension, and as warps, the elastic braid so produced is a 70 much superior product in that the formation of the interlocking threads around the elastic not only eliminates the usual "creeping", but binds the elastic strand tightly and yet permits a stretch of the same to its elastic 75 limit.

By means of the twirling, which produces the loops and pockets P, a far superior elastic lace braid has been made on a one thread 80 lace machine, without limiting the lace designs which may be incorporated.

By using spools containing great yardage, I eliminate the necessity of tying the elastic strands, thus forming knots, which is necessary in the case of the use of bobbins, 85 on account of the small yardage carried by a bobbin. These knots, when the fabric is used on underwear, often causes chafing and are highly objectionable.

Of course, the elastic lace braid illustrated, 90 and the particular mechanism described in connection with the process, may be varied in many ways without departing from the invention herein set forth and hereafter claimed.

I claim:—

1. An elastic lace braid having elastic warps, transverse non-elastic braiding threads interconnecting the elastic warps and holding the braid against substantial lateral extension, and double non-elastic threads connecting the transverse threads at the points same cross each warp to bind the same firmly thereto.

2. An elastic lace braid having elastic warps, non-elastic transverse braiding threads interconnecting the elastic warps and holding the braid against substantial lateral extension, and a pair of non-elastic threads for each warp twirled loosely along 110 the side of said warp and binding the transverse threads to the warp at the points said transverse threads cross same.

3. An elastic lace braid having elastic warps, non-elastic transverse braiding threads interconnecting the elastic warps and holding the braid against substantial lateral extension, and non-elastic threads connecting the transverse threads and warp only at the points said transverse threads 115 cross the warp and being twirled to permit each warp to be stretched to its elastic limit without tensioning said twirled threads.

4. An elastic lace braid having elastic warps, non-elastic transverse braiding threads interconnecting the elastic warps and holding the braid against substantial lateral extension, and a pair of non-elastic threads for each warp twirled loosely along 125 the side of said warp and binding the trans-

verse threads to the warp at the points said transverse threads cross same.

5. An elastic lace braid having elastic warps, non-elastic braiding threads interconnecting the elastic warps, and non-elastic threads loosely twirled and passing from side to side of each elastic warp and binding said first threads to said warps.

In testimony whereof I have signed my
10 name to this specification.

HUGO MEHLER.
